UNITED STATES PATENT OFFICE.

AMIE V. PAQUETTE, OF CHICAGO, ILLINOIS, ASSIGNOR TO L. B. ALLEN CO., OF CHICAGO, ILLINOIS, A CORPORATION OF ILLINOIS.

SOLDERING-IRON.

1,161,960.

Specification of Letters Patent. Patented Nov. 30, 1915.

Application filed August 6, 1914. Serial No. 855,354.

To all whom it may concern:

Be it known that L. AMIE V. PAQUETTE, a resident of Chicago, in the county of Cook and State of Illinois, have invented certain new and useful Improvements in Soldering-Irons, of which the following is a full, clear, and exact description:

The invention relates to soldering irons of the self-heating type.

One object of the invention is to provide an improved soldering iron which may be economically operated by a small jet or flame of gas to which sufficient air is admitted to promote combustion and which will not back-fire at an air-inlet.

Another object of the invention is to provide an improved mixing-tube which is provided with means at its outlet-terminal for causing the air and gas to mingle and for directing the flame into the soldering-point.

A still further object of the invention is to provide an improved detachable connection for securing the point to its supporting tube to facilitate removal or replacement of the bit.

The invention consists in the several novel features hereinafter set forth and more particularly defined by claims at the conclusion hereof.

In the drawings: Figure 1 is a side elevation of a soldering iron embodying the invention. Fig. 2 is a central longitudinal section. Fig. 3 is a section taken on line 3—3 of Fig. 2. Fig. 4 is a section taken on line 4—4 of Fig. 2.

The improved soldering iron comprises a handle 8; usually made of wood, a gas pipe 9, extending longitudinally through the handle, a shut-off cock 10 connected to one end of pipe 9 and adapted to be connected to a flexible tube 11 from a suitable source of gas supply, and a coupling member 12, which is secured by screw-thread to one end of pipe 9. A nozzle 14 is secured to the coupling 12, an opening 15 being formed through said member to conduct gas from pipe 9 to said nozzle. Coupling 12 comprises a ring 16, a ring 17, in which opening 15 is formed and longitudinally extending connecting-ribs 18 between said rings. A mixing-tube 19 is secured in ring 16 by a screw 20. Nozzle 14 is smaller in cross-sectional area than tube 19 and extends entirely across the opening between rings 16 and 17 through which air enters the mixing tube

and around the nozzle. By thus extending the nozzle entirely across the opening between the rings and into the mixing-tube, the gas delivered into the mixing-tube draws the air into said tube through the space 60 between the nozzle and the mixing-tube, so that the air and gas will be well mixed in the tube to minimize back-firing, which may injure the hand of the operator. In practice, the operator sometimes places 65 his hand around the coupling 12 and the handle, and if the flame back-fires at such time, there is danger of injuring his hand. This construction has been found to effectively minimize back-firing.

A soldering-point 21 is secured to a burner-tube 22, having holes 23 therein for the escape of the products of combustion. The inner end of tube 22 is secured to a collar 24 which is adjustably secured by a screw 75 25 to the mixing-tube 19. Collar 24 has lugs 26 fitting in the tube 22 and air-openings 27 are formed between said lugs. A socket or recess 28 is formed in the soldering-point to permit the flame to pass into and to more 80 effectively heat the point. By adjusting the point to or from the flame, heating of the iron may be regulated. Small outlets 40 for the products of combustion are formed in the point 21.

The discharge-terminal of mixing tube 19 is formed with inwardly and forwardly extending tongues 30. These tongues serve to further mix the air and gas before reaching the point of combustion and tend to direct 90 the flame toward the point.

Tube 22 is formed of thin or sheet metal to avoid excessive weight, and is perforated all over as at 23. By forming this tube of sheet metal, it does not act to conduct much 95 heat to collar 24 so that the iron may be used continuously without heating the handle.

In some cases, it is desirable to use points, which are usually made of copper, of different shapes for different kinds of work and to facilitate changing of the points, and to provide a joint which will not be affected by heat, a detachable interlocking connection is provided between the point and the tube 22. 100 This connection consists of studs 31 secured to the point and annular slots 32 which operate similarly to a bayonet catch to removably lock the point and tube 22 together. Portions 33 of the slots are angled so as to 110

act as cams which will force the shoulder 34 on the point against the outer end of tube 22. Obviously, the point may be removed from the tube 22 by partial relative rotation 5 of the tip and tube and then separating them longitudinally. This connection facilitates changing of the points when desired, and can be released when the point is hot. If desired, collar 24 and tube 22 may be removed from tube 19 and the latter may then 10 be used as a blow torch.

The invention exemplifies a soldering iron which is simple in construction, economical in operation and in which there is no danger 15 of back-firing at the air inlets to the mixing tube.

The invention is not to be understood as restricted to the details set forth since these may be modified within the scope of the appended claims without departing from the 20 spirit and scope of the invention.

Having thus described the invention, what I claim as new and desire to secure by Letters Patent, is:

25 1. In a gas-heated soldering iron, the combination of a handle having a gas-pipe therein, a mixing tube in separated relation from the handle, a coupling between the handle and the mixing tube having an air- 30 inlet and having one of its ends connected to said pipe and the other to said tube therein, a nozzle connected to one end of said coupling and extending entirely across said inlet and terminating in the mixing tube, 35 and a soldering point connected to said tube.

2. In a gas-heated soldering iron, the combination of a handle having a gas-pipe therein, a mixing tube in separated relation from the handle, a coupling between the 40 handle and the mixing tube comprising a ring secured to the gas-pipe, a ring in which the mixing tube is secured, and longitudinal connecting ribs between the rings, a nozzle connected to the ring which is secured to the 45 gas-pipe, and extending entirely across the space between said rings and into the mix-

ing tube, and a soldering point connected to said tube.

3. In a gas-heated soldering iron, the combination of a handle, a gas-supply pipe 50 connected to the handle, a nozzle connected to said supply, a mixing tube supported to receive fluid from said nozzle, having inwardly extending tongues at its discharge terminal, and a soldering point connected to 55 the mixing-tube.

4. In a gas-heated soldering iron, the combination of a handle, a gas-supply pipe connected to the handle, a nozzle connected to said supply, a mixing tube supported to 60 receive fluid from said nozzle, having inwardly extending tongues at its discharge terminal and a coupling between said pipe and said tube having an air-inlet connected to the mixing tube.

5. In a gas-heated soldering iron, the combination of a handle, a gas-supply pipe connected to the handle, a nozzle connected to said supply, a mixing tube supported to receive fluid from said nozzle, having inwardly extending tongues at its discharge terminal, a perforated tube removably secured to the mixing-tube, and a soldering point secured to the perforated tube.

6. In a gas-heated soldering iron, the 75 combination of a handle, a gas-supply pipe connected to the handle, a nozzle connected to said supply, a mixing tube supported to receive fluid from said nozzle, a coupling between the handle and said mixing tube 80 having an air inlet therein, a collar adjustably secured to the mixing tube, a perforated sheet metal burner tube, the collar having lugs with openings therebetween to which one end of the burner tube is secured, 85 and a soldering point secured to the other end of the burner tube.

AMIE V. PAQUETTE.
